UNITED STATES PATENT OFFICE.

EMIL J. FRANCK, OF PHILADELPHIA, PENNSYLVANIA

KNITTING-MACHINE.

1,218,073.

Specification of Letters Patent.

Patented Mar. 6, 1917.

Application filed July 3, 1916. Serial No. 107,253.

To all whom it may concern:

Be it known that I, EMIL J. FRANCK, a citizen of the United States, and a resident of Philadelphia, in the county of Philadelphia and State of Pennsylvania, have invented certain new and useful Improvements in Knitting-Machines, of which the following is a specification.

The principal objects of the present invention are to provide a comparatively simple, durable and reliable machine for knitting stockings, with fashioned heels and toes and shaped calf portions, even of fine gage; to facilitate and improve the construction and arrangement by which the calf needles are brought into and out of action; to improve the combination and arrangement of parts so as to produce neat and attractive work where the calf is widened; to facilitate the insertion and removal of the calf needles in respect to the needle head; to obtain in a machine of the character described the advantages of a rotating needle head and latch-needles; to avoid undue strain on the yarn where the calf needles are employed in shaping the calf portion of the stocking; and to provide for adjustably controlling the position of the calf needles when out of action.

The invention will be claimed at the end hereof, but will be first described in connection with the accompanying drawings, forming part hereof, and in which—

Figure 1, is a side view, partly in section, of a machine embodying features of the invention.

Fig. 2, is an end view, partly in section, of the same.

Fig. 3, is a horizontal sectional view with parts omitted.

Fig. 4, is a transverse sectional view with parts omitted.

Fig. 5 and Fig. 6 are views, drawn to an enlarged scale, and illustrating features illustrated in Fig. 4.

Fig. 7, is a sectional view, with parts omitted, of the needle cylinder.

Fig. 8, is a sectional view taken on the line 8—8 of Fig. 7, partly diagrammatic.

Fig. 9 is a sectional view drawn to an enlarged scale illustrating the needle cylinder.

Fig. 10, is a sectional view taken on the line 10—10 of Fig. 9.

Fig. 11, is a detached sectional view illustrating parts shown in Fig. 9 but taken on a different plane.

Fig. 12, is a view drawn to an enlarged scale of a web holder.

Figs. 13 and 14 are diagrammatic views illustrating features hereinafter referred to, and

Fig. 15 is a side view of a modified form of jack.

In the drawings 1 is a revoluble needle cylinder having a circular set of inclined needle grooves 2 and having a segmental set of inclined needle grooves 3 arranged at an inclination to and inside of the first set of needle grooves 2 and extending below the latter. The needle cylinder is revolubly mounted on a base 4 and the inclined needle grooves 3 may be cut on the face and part way around the needle cylinder proper, which is somewhat conical, while the inclined needle grooves 2 are cut on the face of a conical addition 5 to the needle cylinder which is connected with it as by a ring 6, so that the cylinder and the addition revolve together. There are regular needles 7 in the circular set of grooves 2 and these are of the latch type and some of them have bits 8 that are longer than the bits of the others, which is a customary provision for use in connection with fashioning the heels and toes. 8 are leg fashioning needles arranged to coöperate with jacks 9 and the needles 8 and their jacks 9 are arranged in the segmental set of grooves 3. The segmental set of grooves 3 extend down below the circular set of grooves 2 for a purpose that will be presently described in connection with the means for connecting and disconnecting the bits of the needles 8 and their jacks 9.

While the circular and segmental sets of needles are each inclined and are arranged at an inclination to each other, still they knock off stitches in the same horizontal plane. 10 are web holders arranged in an appropriate bed 11, carried by a post 12, and 13 is a cam for working the web holders. 14 is a latch guide and it is also carried by the post 12. The cam ring 15 and its accessories for working the regular needles 7 is also carried by the post 12. The post 12 has jointed connection with the part 14 which it carries, so that it may be turned up out of the way when required. 16 is a sector-like table revoluble with the needle cylinder and connected with it, for example, by the ring 6. This sector-like table is provided with radiating grooves 17, of which there is one

opposite each groove 3 of the segmental set of needle grooves. 18 are pivotal pressers in the groove 17 and adapted to be positioned in such a way that their free ends operating 5 on bends in the shanks of the needles 8 serve to connect and disconnect them with their jacks 9. These pressers operate below the regular needles 7. 19 and 20 are tappet arms connected with the ends of a yoke slidably 10 mounted in the post 12 and these tappet arms operate to position the pressers as they are rotated with the cylinder. The pressers are provided with depending lugs 21. The depending lugs of the series terminate at 15 points progressively farther from the needle cylinder considering them from the edges of the table toward the center thereof. This is indicated by the use of heavy lines in Fig. 1. As the cylinder is rotating the tappet arm 19 20 is moved progressively outward and so needles 8 at the ends of the segmental set are thrown into action, one after another. After all of the needles 8 have been brought into action and have been permitted to act 25 for a time, the tappet arm 20 is brought into range of lugs 22 projecting upward from the pressers and arranged in the same circle, so that all of the pressers are turned down and disconnect the needles 8 from their jacks 20 30. There is sufficient friction for holding the pressers 18 in the positions in which they are put by the tappet arms. 23 is a ring that encircles the needles 8 and it can be lifted by a yoke 24 and when this is done, 35 the needles 8 can be taken out of the machine and replaced by others. 25 is a spring for holding the needles 7 in their grooves and permitting of their renewal. 26 is a segment of a ring provided with a flange 27 40 which projects through a suitable slot in the needle cylinder and forms a stop for the bits of the needles 8. This ring 26 can be adjusted by loosening the set screw 28 and manipulating the screw 29, which has a conical point, that takes into a hole in the ring section 26. 30 is a lever that is used for giving the jacks 9 an additional movement when the stocking is finished. 32 and 33 are levers which control the cams of the regular 45 needles 7 and which are used in connection with the operation of fashioning the heels and toes, which operations really form no part of the present invention but certain instrumentalities used in connection with them 50 are mentioned so as to develop the relation of the mechanisms which do form part of the invention to certain usual parts of the machine. In passing it may be said that in the heel and toe fashioning and widening, 55 picker mechanism may be employed but it is not illustrated, since it is well understood and has nothing to do with the present invention. Inasmuch as some of the needles 7 have short bits and some of them have long 60 bits, as indicated by dotted lines in Fig. 9,

it may be said that this has to do with getting some of these needles into and out of action in order to fashion the heels and toes.

A description will now be given of means 70 for operating the parts that enter into the present invention and incidentally reference will be made to certain features of these means which are not directly concerned with the present invention but are 75 concerned with other known features of the machine.

34 is a main shaft on which is mounted a sleeve 35 provided with tight and loose 80 pulleys 36 and 37, a clutch member 38, and a pinion 39. The pinion 39 meshes with a toothed wheel 40 connected by a link 41 with the arm 42 of a toothed quadrant 43 journaled at 44. The quadrant 43 meshes with a pinion 45, loose on the shaft 34, and provided with a clutch member 46. In consequence of this arrangement the pinion 39 rotates continuously in one direction and the pinion 45 is reciprocated. The purpose of this is to provide reciprocating motion 90 for the needle cylinder during the operation of widening and narrowing the heels and toes and continuous rotary motion for knitting the other parts of the stocking. 47 is a clutch member splined to the shaft 34 95 and adapted for engagement with either the pinion 39 or the pinion 45. The needle cylinder is driven from the shaft 34 by gears 48, 49, 50 and 51. The shipper arm 52 of the clutch member 47 is controlled by 100 an edge-cam 53 mounted on a counter-shaft 54, Fig. 3. This cam is controlled so as to shift the clutch and produce proper dwells between its movement. There is a pawl arm 55, shown in dotted lines in Fig. 105 2, and it is mounted on the shaft 54 and actuated from the quadrant 43 by a sliding connection 56. This pawl arm carries pawls 57 and 58. The pawl 57 drives the pattern chain wheel 59 continuously and the pawl 110 58 drives the cam 53 one revolution and then works back and forth idly in a space 60 formed by the omission of one of the teeth so that the cam comes to rest. A pattern chain 61 is provided with lugs, of 115 which one 62 is shown, that abuts on lugs 63 (of which one is shown) on the cam and so turn it sufficiently to permit the pawl 58 to resume its described operation. There is a double face cam 64 mounted on the shaft 120 65 and one face of this cam acting on one end of the lever 66 causes the other end thereof, operating through a link 67, to properly shift the yoke that carries the tappet arms. The other face of this cam 64 125 operates upon one arm 68 of a hollow-shaft 69 mounted on another shaft 70. The other arm 71 of the hollow shaft operates through the intervention of the link 72, and cam lever 30. Inasmuch as the hollow shaft 130

69 is mounted to turn freely on the shaft 70 it may be said that the shipper 52 is connected with the shaft 70 and that the shaft 70 is provided with arms which through the 5 intervention of links 73 and 74 operate the cam levers 33 and 32, which as has been said have to do with the operation of throwing in and out needles during the toe and heel fashioning.

10 A description will now be given of the means for driving the cam 64 intermittently and with appropriate dwells in its movement. There is a pawl arm 76 mounted on the shaft 65 and reciprocated by an eccentric 15 77 on the shaft 34, through the intervention of the strap 78. This pawl arm 76 is provided with a pawl 79 wide enough to operate on the teeth of two wheels 80 and 81, both of which are loose on the shaft 65, 20 and of which 81, is connected with the cam 64. By reference to Fig. 5 it will be observed that the wheel 80 is larger than the wheel 81 and that the wheel 80 is provided at intervals with deep teeth 82, so that the 25 pawl 79 can only drive the wheel 81 when it is able to reach its teeth by entering one of the deep teeth 82. This produces comparatively slow movement of the wheel 81. There is on the face of the wheel 81 a guard 30 plate 83 capable of a range of movement concentric with but independent of the wheel. This guard plate is shifted in one direction by a spring 84, shown in dotted lines in Fig. 5, and in the other direction 35 by a crank arm 85. The guard plate is provided with high teeth 86, higher than the teeth on either of the wheels 81 and 80, so that the pawl 77 can ride on them without producing motion of either of the wheels 40 81 or 80. The crank arm 85 is fast on a shaft 87, Fig. 3, which has another crank arm 88 and this crank arm 88, when turned, effects movement of the guard plate 83 to permit the pawl 77 to resume its normal operation. The crank arm 88 is turned by 45 projections on a lever 89 mounted loosely on the shaft 65 and operated through a link 90 connected with one arm 91 of a bell-crank-lever the other arm 92 of which is 50 in range of and is operated by the pattern chain 61, to which reference has been made. When the cam 64 is at rest, with the pawl 77 working on one of the high teeth 86 of the guard, the pattern chain operating 55 through the parts 92, 91, 90 and 89 shifts the guard and so permits the pawl 77 to resume its ordinary operation.

Fig. 14 illustrates diagrammatically that there are two web-holders between each of 60 the regular needles 7 that extend between the ends of the group of needles 8 and that there is one web-holder between each of the needles 7 and 8 which tends to produce uniformity in the work.

65 Fig. 13 illustrates, considering the lower

part of the sheet to be the center of the needle cylinder, how the calf needles 8 are inside of the regular needles 7 and how the web-holders project the loop X, which is the second loop, from the top in such a way that 70 the calf needles 8 when they come into action pass through the loop X. There is an advantage in having the calf needles inside of the regular needles for as the calf needles come into action and take the thread, the 75 latter is not subjected to the same strain as it would be if the calf needles were outside of the regular needles. Again the making the objectionable holes in the fabric is avoided. It is the hook 93 on the web-holder 80 10 that carries the loop X into the position shown in Fig. 13. The loop Y Fig. 13, is back of the hook 93, for example, at the location indicated by 94, Fig. 12. The slot 95 in the web-holders accommodates the 85 ring 96 and so properly guides the web-holders.

The toe, foot, heel and ankle part of the stocking are knitted on the regular needles 7 as is well understood. The calf is widened 90 by bringing the extra needles 8 into action along with the needles 7. The first step in this operation is to throw the jacks 9 into action in connection with their knitting cams and to actuate the pressers 18 one after 95 another in the manner described so as to permit the needles 8 to come into action one after another to produce the widening of the calf portion. Thereafter the knee portion of the stocking is knitted and upon 100 its completion the pressers throw out all of the calf needles and the jacks 9 are put out of action. The mechanism for doing these things has been above described and its action is, of course, timed for their accomplishment. Referring to Fig. 15 the jack 9^a is provided with a comparatively wide opening 9^b and with a comparatively narrow opening 9^c and the purpose is to operate the needles in such a way that they make 110 first a short stroke and then strokes of regular length. When making a short stroke the needle bits are in 9^b and when making full strokes the needle bits are in 9^c.

What I claim is:

1. In a knitting machine the combination of a revoluble needle cylinder having a circular set of inclined needle grooves and a segmental set of inclined needle grooves arranged at an inclination to and inside of 120 the first set and extending below the latter, regular needles in the circular set of grooves, leg fashioning needles and their jacks in the segmental set of grooves, a sector-like radiating set of pivotal pressers revoluble 125 with the needle cylinder and arranged below the circular set of needle grooves and adapted to connect and disconnect the leg fashioning needles and their jacks, a tappet device for positioning the pressers as they ro- 130

tate with the cylinder, and means for operating said parts, substantially as described.

2. In a knitting machine a revoluble needle cylinder having a circular set of inclined needle grooves and a segmental set of inclined needle grooves arranged at an inclination to and inside of the first set and extending below the latter, regular needles in the circular set of grooves, leg fashioning needles and their jacks in the segmental set of grooves, a sector-like table revolving with the cylinder and provided with radiating slots of which one is opposite the lower portion of each groove of the segmental set, pivotal pressers in said notches adapted to be positioned for connecting and disconnecting the leg-needles and jacks, a tappet device for positioning the pressers as they are rotated with the cylinder, and means for actuating said parts, substantially as described.

3. In a knitting machine, a revoluble needle cylinder having a segmental set of inclined needle grooves and a circular set of inclined needle grooves arranged at an inclination to and inside of the first set and extending below the latter, leg needles and their jacks in the segmental set of grooves, a knitting cam for the jacks, a cam for putting the jacks into and out of action, a set of radiating pressers revolvable with the cylinder and arranged below the circular set of needle grooves and adapted to progressively connect the needles and jacks, a tappet device for operating the pressers, and means for actuating said parts, substantially as described.

4. In a knitting machine the combination of a revoluble needle cylinder, leg-needles, jacks for the leg-needles, a radiating set of pressers carried by the cylinder and provided with projections terminating progressively from the ends toward the center of the set at points farther from the cylinder, a tappet device coöperating with said projection, and means for operating said parts.

5. In a knitting machine the combination of a revoluble needle cylinder, leg-needles

and their jacks, a sector-like table carried by and projecting from the cylinder and provided with radiating slots, pressers pivotally mounted in said slots and projecting beyond the plane of the table, a tappet device coöperating with the projecting portions of the pressers, and means for actuating said parts.

6. In a knitting machine the combination of a generally conical needle cylinder having a segmental set of needle grooves, a section of needle cylinder mounted on and around the first mentioned cylinder and of less conical inclination and having a circular set of needle grooves terminating above the segmental set of needle grooves to provide space, leg-needles and their jacks in the segmental set of grooves, jack releasing mechanism in said space, and means for actuating said parts.

7. In a knitting machine the combination of two conical needle cylinders in nested relation with space between, a segmental set of needle grooves on the inner cylinder, a needle retaining ring section overlying said grooves, and means for shifting said ring, substantially as described.

8. In a knitting machine the combination of a needle cylinder having a segmental set of needle grooves and a circumferential slot at the base of and substantially co-extensive with said set of needle grooves, a ring section having a needle-stop-flange projecting into said slot, and means for adjusting the ring section.

9. In a knitting machine the combination of a generally conical needle cylinder having a segmental set of needle grooves, a section of needle cylinder mounted on and around the first mentioned cylinder and of less conical inclination and having a circular set of needle grooves terminating above the segmental set of needle grooves to provide space, leg-needles in the segmental set of grooves, leg needle releasing mechanism in said space, and means for actuating said parts.

EMIL J. FRANCK.
